UNITED STATES PATENT OFFICE.

FRANK SZCZESNY, OF NORWICH, AND TEOFIL JAKUBOWSKI, OF BRIDGEPORT, CONNECTICUT.

SHADE-ROLLER AND CURTAIN-ROD SUPPORT.

Application filed June 4, 1926. Serial No. 113,642.

This invention relates generally to shade-rollers and curtain-rod supports such as used at windows and the like. The invention having more particular reference to a novel 5 type of combined shade-roller and curtain-rod support.

The invention has for an object the provision of an adjustable shade-roller and curtain-rod support.

10 A further object of the invention is the provision of an adjustable shade-roller and curtain-rod support of cheap construction and low cost.

15 For further comprehension of the invention, and of the objects and advantages thereof, reference will be had to the following description and accompanying drawings, and to the appended claims in which the various novel features of the invention are 20 more particularly set forth.

Fig. 1, of the drawings, illustrates our improved combined shade-roller and curtain-rod support in place on a window frame with a shade and curtain attached thereto, 25 as it would appear when in use.

Fig. 2, is a top plan view thereof.

Fig. 3, is a front perspective view of our improved combined shade-roller and curtain-rod support.

30 Fig. 4, is a vertical sectional view taken on the line 4—4 of Fig. 3.

Fig. 5, is a similar view to that shown in Fig. 3, illustrating a modification of our improved device.

35 Fig. 6, is a face view of a modification of the support.

Fig. 7, is a vertical sectional view taken on the lines 7—7 of Fig. 6.

Fig. 8, is a face view showing a second 40 curtain bracket secured to the supports shown in Fig. 5.

Fig. 9, is a top plan view of the same.

As here embodied our improved combined shade-roller and curtain-rod support comprises, a support 10, of any suitable design and shape, having apertures 11, to accommodate screws or the like, as a means of attaching the support 10 to the upper or top portion of a window frame, as clearly shown 45 in Fig. 1. The support 10, is provided with curved elements 12, adapted to slidably support a shade-roller bracket 13, having its extremity 14 bent or formed, at right angles thereto, and provided with an aperture 15, 50 and elongated slots 16, extending from the

upper and bottom edge of the extremity 14, and located above and below the said aperture 15, so as to support a shade-roller, such as commonly used. It being understood that the said shade-roller bracket is adapted 60 to support a shade-roller at either end, by slidably engaging the shade-roller bracket in either end of the support 10.

The curtain-rod bracket 17 is provided with an extended element 18, extending 65 therefrom below the bracket 17. The curtain-rod support 17 is also provided with a curved extremity 19, positioned at right angles thereto, and having suitably attached thereto, a vertical pin 20, extending upward 70

therefrom, adapted to engage a curtain-rod 40, such as commonly used. The extremity of the support 17 is formed in a substantially cylindrical loop for providing a socket for the pin 20 which is adapted to retain the lat- 75

ter in upright position. It should be understood that the curved portion 19 of the support 17 is adapted to be disposed within the hem of a curtain and is also adapted to retain the edge portions of the curtain in a 80

curved or rounded shape, the manner in which the pin 20 is mounted on the support 17 being particularly adapted to eliminate sharp corners and projections for prevent- 85

ing tearing of the curtain when the lat- ter is disposed over the support 17. It being understood that the shade-roller 80

bracket 13 may be extended so as to accom- modate shade-rollers 41 of various lengths, and that the said shade-roller bracket 13 may 90

be held in any desired extended position by a screw 24, located adjacent to a suitably formed notch 25 at the extremity of the 95

shade-roller bracket. The extended element 18 is provided with an elongated slot 21 having enlarged extremities 22, so as to per- 100

mit the said curtain-rod bracket 17 to be slidably attached to the support 10, by means of a screw 23, threadedly attached to the sup- 105

port 10. It being understood that the en- larged extremities 22, will permit the cur- 110

tain-rod support 17 to be engaged or dis- engaged with the support 10 by merely loos- ening the said screw 23, and that the curtain- rod support 17 may be extended so as to ac- 105

commodate curtain-rods of various lengths, and by tightening the screw 23, that curtain- rod support 17 may be held in any desired extended position.

Referring in particular to Fig. 5 of the ac- 110

companying drawings, in which we have illustrated a modification of our improved device, the support 26, has an upper element 27, and a lower element 28, provided with curved edges, 29 and 30, respectively adapted to slidably support a curtain-rod bracket 31, and the shade-roller bracket 13. The support 26 is provided with apertures 32, to accommodate screws 33, as a means of attaching the support 26, to the upper or top portion of a window frame. The said screws 33, being suitably located, so as to permit the head of the said screws 33, when the said screws are screwed in, to make contact with the edges of the shade-roller bracket 13, and the curtain-rod bracket 31, so as to hold the shade-roller bracket 13, and the curtain-rod bracket 31 in any desired extended position, for the purpose as heretobefore set forth.

Referring in particular to Figs. 6 and 7 of the accompanying drawings, in which we have illustrated a further modification of our improved device, the support 26, has 25 slidably attached thereto by screws 35 engaging member 34, adapted to engage one edge of the shade-roller bracket 13, and one edge of the curtain-rod bracket 31, so as to more firmly hold the shade-roller bracket 13 and the curtain-rod bracket 31 in any desired extended position.

Referring in particular to Figs. 8 and 9, of the accompanying drawings, in which we have illustrated another modification of our 35 improved device, the above mentioned curved edges 29 and 30, are adapted to slidably sup-

port the above mentioned curtain-rod bracket 31 and a second curtain-rod bracket 31', adapted to engage the above mentioned curtain-rod 40 and a second curtain-rod 40', respectively. It being understood that the second curtain-rod bracket 31' is provided with a curved extremity 19', having attached thereto, a vertical pin 20', extending upward therefrom, the said curved extremity 19' being of suitable or sufficient length to extend beyond the above mentioned curved extremity 19.

Having thus described our invention, what we claim as new, and desire to protect by 50 Letters Patent of the United States, is as follows:

A device of the class described comprising spaced apart brackets adapted to be secured to a wall, extensions on each of said brackets 55 each comprising an inwardly disposed curved portion, a socket member formed on the end of lock of said curved portions, comprising an integral projection of said curved portion of a width less than the width thereof, and 60 formed substantially in the shape of a cylinder, a pin mounted in upright substantially vertical position in each of said sockets extending to the upper edges of said curved portions and a curtain rod having apertures in the end portions thereof, for receiving said pins mounted on the latter for forming a continuance of said curved portions.

In testimony whereof we have affixed our signatures.

FRANK SZCZESNY.
TEOFIL JAKUBOWSKI.
